(57) **CLAIM**

I claim the ornamental design for a coffee maker, as shown and described.

DESCRIPTION

FIG. 1 is a top, left perspective view of a coffee maker of the present invention.

FIG. 2 is a right, side view of the coffee maker depicted in FIG. 1.

FIG. 3 is a front view of the coffee maker depicted in FIG. 1.

FIG. 4 is a left, side view of the coffee maker depicted in FIG. 1.

FIG. 5 is a rear view of the coffee maker depicted in FIG. 1.

FIG. 6 is a top view of the coffee maker depicted in FIG. 1.

FIG. 7 is a bottom view of the coffee maker depicted in FIG. 1.

FIG. 8 is a bottom, left perspective view of the coffee maker depicted in FIG. 1; and,

FIG. 9 is a top, left perspective view of the coffee maker depicted in FIG. 1 with removable lid and base portions illustrated in a removed configuration to show aspects of the design that are not visible with the lid and base portions in place.

In the drawings, the broken lines depict portions of the article that form no part of the claimed design.

1 Claim, 9 Drawing Sheets
